STUDIO COUCH

Claude A. Hughes, High Point, N. C.

Application February 23, 1939, Serial No. 258,034

3 Claims. (Cl. 5—31)

This invention relates to an improved construction of studio couch.

It is an aim of this invention to provide an improved studio couch or combination sofa and bed having improved means of simple construction for automatically raising the bed portion to an operative position by swinging the top half of the couch to an extended inverted position.

Still a further object of the invention, is to provide an improved couch or sofa of the class described provided with a foldable swivelly mounted end table and ash trays pivotally mounted on the end posts of the couch to close into said posts when not in use.

Still a further aim of the invention, is to provide a couch having a frame in which two halves of a bed may be folded when not in use, one of said halves functioning as a seat bottom when the couch is in a closed or folded position.

Other objects and advantages of the invention will hereinafter become more fully apparent from the following description of the drawings, which illustrate a preferred embodiment thereof, and wherein:

Figure 1 is a front elevational view of the invention,

Figure 2 is a vertical sectional view taken along the line 2—2 of Figure 1,

Figure 3 is an enlarged sectional view taken along the line 3—3 of Figure 2,

Figure 4 is a fragmentary top plan view showing the couch in an extended position and with the bed mattress removed, and

Figure 5 is a transverse vertical sectional view, partly in elevation, showing the position of the parts when in an extended position, as seen in Figure 4.

Referring more particularly to the drawings, wherein like reference characters designate like or corresponding parts throughout, 10 designates generally a couch constructed in accordance with the invention and including the front legs 11 and back legs 12 which support the frame, designated generally 13.

Front legs 11 are elongated to form the posts 14 which are secured to the ends of the frame 13 contiguously with its front sill 15. The back legs 12 are connected to the rear sill 16 and at the opposite ends of the frame 13 to co-act with legs 11 in supporting the frame at its four corners. A rail 17 is secured to the outer side of the sill 16 to support a back rest 18 which projects upwardly and rearwardly therefrom. Arms 19 are mounted on the upper ends of the posts 14 and secured to the back rest 18 at opposite

ends of the couch 10 to complete the framework thereof.

The ends of the sills 15 and 16 are connected by the end members 20 which complete the frame 13, which is divided horizontally to form the upper section 21 and the lower section 22 which are hinged at 15' along the front sill 15.

Upper section 21 is provided with the seat 23 including the padding 24 and springs 25. Springs 25 are supported by a seat bottom 26 mounted in the bottom part of section 21 and comprising the three sided frame 27 to which is connected the slats 28 by means of the coil springs 29 to form a resilient bottom for the seat springs 25.

A section or half of a bed bottom 30, corresponding in construction to the seat bottom 26 is mounted within and in the lower part of section 22 when the couch 10 is folded, as seen in Figure 2. The longitudinal side 27 of the bed bottom 30 is adapted to rest on the flange 31, when the couch is closed, disposed adjacent to the sill 16. The end rails 32 of the frames 27 of the bottoms 26 and 30 are connected at their free ends by the links 33, which extend between the end rails of the two bottoms and which are disposed within and adjacent to the opposite ends of the frame 13 when the couch is closed.

Levers 34 are pivotally mounted at 35 intermediate of their ends to the inner sides of the ends 20 and are connected at their corresponding ends by the links 36 to the frame of the bed bottom 30. Links 36 are pivotally connected to levers 34 and are likewise pivotally connected to the end rails 32 adjacent their secured ends, as best seen in Figure 5. Links 37 are pivotally connected to the opposite ends of the levers 34 and to the end rails 32 of the bottom 26 adjacent their free ends by the pivots 38 which connect links 33 to bottom 26.

The transverse slats 28 of the bottoms 26 and 30 are connected at their free ends by links 39 which bridge the space between said bottoms when the couch is in an extended position, as seen in Figure 5, to support a mattress 40 which extends the length of and across the bottoms 26 and 30 to form a bed. To assist in drawing bottom 30 downwardly into section 22 when section 21 is moved to its folded position, contractile coil springs 41 are provided which are secured to the lower edge of the sill 15 and to a rod 42 which extends the length of bottom 30 and which is attached thereto at its ends with its intermediate portion bowed downwardly as seen in Figures 2 and 5. A flexible handle member 43 is attached to the upper edge of sill 16, which is 55

a part of section 21, for lifting and swinging said section from its folded position, as seen in Figure 2, to its extended position as seen in Figure 5. Legs 44 are secured to this same portion of sill 16, being pivotally mounted on the outer side thereof to lie along sill 16 when section 21 is folded and to be swung to a perpendicular position when the section is extended to support the free end thereof. Stops 45 may be provided to retain legs 44 in a perpendicular position.

Posts 14 are provided with the recesses 46 to receive the ash trays 47 which are pivotally mounted at 48, at their lower converging ends and which are fan shaped as seen in Figure 5, to form the enlarged open mouths 49 at their upper ends. The ash trays 47 are adapted to be normally held in a closed position by the spring latches 50 with their open ends 49 retracted in posts 14. Handles 51 are provided for pulling 20 the trays 47 outwardly to an open position for use.

An end table or tray 52 is mounted at one end of the couch 10 by means of a bracket 53 secured to the outer edge of one of the posts 14 and in which is journaled the vertical portion of a rod 54 which is bent intermediate of its ends to provide the horizontal portion which is pivotally attached to the underside of the table or tray 52 by the straps or loops 55. A diagonal brace 56 is pivotally connected at one end to the vertical portion of rod 54 with its opposite end adapted to engage a stop 57 to support the table 52 in a horizontal position. Table 52 is thus foldably and swivelly mounted and when not in use may be folded against the arm 19 by lifting the free edge of the table, to release brace 56, after which the brace is swung inwardly against the rigid brace 58 to permit table 52 to swing downwardly, to a collapsed position, after which it is turned relatively to post 14 to position it against one end of the couch.

The operation of the bed and seat portion of the couch 10 is as follows: with the couch 10 in a folded or closed position, as seen in Figures 1 and 2, seat 23 is adapted for use as a sofa seat. When the couch 10 is to be used as a bed, handle 43 is grasped to swing section 21 upwardly and outwardly, through an arc of substantially 180°, to its extended position after which the legs 44 are extended, as heretofore explained, to support the free end of section 21. As section 21 moves to its extended position links 33 draw the forward end of bottom 32 upwardly while the links 37 rock the upper ends of the levers 34 in a counter-clockwise direction, from their position as seen in Figures 2 and 5, past the dead center thereby causing links 36 to force the rear end of the bottom 30 rearwardly and upwardly thus raising the bottom to the position, as seen in Figure 5. Bottoms 26 and 30 combine with links 39, when the couch is in an extended position to form a bed adapted to support mattress 40. To close couch 10, section 21 is swung back to its folded position rocking levers 34 in the opposite direction to draw links 36 downwardly thereby pulling the rear end of bottom 30 back to its position in engagement with flange 31. At the same time, the outer ends of the links 33 move upwardly

allowing contractile springs 41 to draw the forward end of bottom 30 downwardly. It will be noted that a substantial space is provided between bottoms 26 and 30 when the couch is in a folded position, as seen in Figure 2, in which a mattress 40 and bed clothing may be contained so that when section 21 is moved to its extended position the bed will be ready for use.

Various modifications and changes in the construction and arrangement of the parts forming the invention may obviously be made and are contemplated and the right is therefore expressly reserved to make such variations and changes as fall within the spirit and scope of the invention as hereinafter defined by the appended claims.

I claim as my invention:

1. A combination sofa and bed comprising a rectangular sofa frame divided horizontally into top and bottom sections, said sections being hinged along their forward sides, a bottom frame mounted in the lower part of the upper section, a seat including springs supported on said upper section by said bottom frame, a bed bottom mounted in the lower section of the sofa frame, links connecting the bottom frame and bed bottom at opposite ends, levers pivotally mounted intermediate of their ends on the ends of said sofa frame, links connected to corresponding ends of said levers and to said bed bottom, and links connected to the opposite ends of said levers and to said bottom frame for raising the bed bottom when the upper section of the sofa frame is swung outwardly to an inverted position, said bed bottom and bottom frame combining when in this position to form a bed.

2. A device as in claim 1, said bed bottom and bottom frame each comprising a U-shaped frame portion, longitudinal and transverse slats mounted in said frame portions, springs connecting the ends of the longitudinal slats and the legs of the frame portions, the adjacent ends of the transverse slats being connected by links, and springs connecting the remote ends of the transverse slats to the intermediate portions of the frame portions.

3. A studio couch comprising a frame formed of superposed sections, said sections being pivotally connected along their front sides, a spring cushion seat mounted on said upper section, a seat bottom mounted in the lower part of said upper section for supporting the springs of said seat, a bed bottom positioned in the lower portion of said frame, links connecting the frames of said bed bottom and seat bottom at their opposite ends and adjacent their forward sides, levers pivotally mounted intermediate of their ends in said frame and on the ends thereof, links connected to corresponding ends of said levers and to the ends of said bed bottom adjacent its opposite sides, and links connected to the opposite ends of said levers and to said seat bottom for raising the bed bottom relatively to the bottom section of the frame when the top section is swung outwardly to an inverted position, said bed bottom and seat bottom being adapted to support a mattress to form a bed when the sections of said frame are extended.

CLAUDE A. HUGHES.
